UNITED STATES PATENT OFFICE.

CARL O. McGRAW, OF DALLAS, AND JAMES L. MARTIN, OF MEXIA, TEXAS.

VACUUM-CONTROLLED ELECTRIC SWITCH FOR GASOLINE FILLING STATIONS.

Application filed August 26, 1921. Serial No. 495,584.

To all whom it may concern:

Be it known that we, CARL O. McGRAW and JAMES L. MARTIN, citizens of the United States, residing in the State of Texas, the said CARL O. McGRAW now residing in Dallas, in the county of Dallas, Texas, and the said JAMES L. MARTIN now residing in Mexia, Limestone County, and State of Texas, have invented new and useful Im-
10 provements in Vacuum-Controlled Electric Switches for Gasoline Filling Stations, of which the following is a specification.

The invention relates to a vacuum controlled electric switch for gasoline filling stations and contains subject matter which is a division of an application filed by us January 6, 1921, Serial No. 435,377 for an automatic vacuum device for gasoline filling stations.

20 The object of the present invention is to provide for an automatic vacuum device of the aforesaid application a vacuum controlled electric switch of simple practical and efficient construction adapted to open and close a motor circuit automatically for stopping and starting the motor of a vacuum pump so that when the receptacle of the gasoline filling station is filled the vacuum pump, which operates to fill the receptacle will be thrown out of operation and when the receptacle is emptied, the pump will be automatically started to refill the receptacle.

It is also an object of the present invention to provide an electrical switch having a vacuum controlled device capable of adjustment for varying the pressure resulting from the exhausting of the air within the device so that a rapid and positive operation of the automatic controlling means will be effected.

40 It is also an object of the present invention to provide means for effectually preventing leakage of air and consequent reduction of the vacuum within the mechanism for controlling and automatically operating the electric switch.

With these and other objects in view the invention consists in the novel construction, combination and arrangement of parts hereinafter fully described, illustrated in the accompanying drawings and pointed out in the claims hereto appended, it being understood that various changes in the form, proportion and minor details of construction, within the scope of the claims, may be resorted to without departing from the spirit

or sacrificing any of the advantages of the invention.

In the drawings in which like characters of reference designate corresponding parts in the several figures;

Figure 1 is a side elevation of the complete apparatus showing a vacuum electric switch for controlling the operation of the vacuum pump.

Figure 2 is an enlarged side elevation of the vacuum device and the electric switch controlled by the same.

Figure 3 is a detail view of the double throw trigger.

Figure 4 is a detail view of the trigger actuating lever.

Figure 5 is a side elevation of a vacuum filling gasoline station equipped with another form of vacuum device for controlling the electric switch.

Figure 6 is an enlarged vertical sectional view of the electric switch and the vacuum device shown in Figure 5.

Figures 7 and 8 are detail views of the members of the double throw trigger.

Figure 9 is a cross section on 9—9 of Fig. 6.

In the accompanying drawings in which are illustrated the electric switch and the automatic vacuum controlling mechanism of the aforesaid application and also another form of the invention which designates the transparent measuring receptacle of the aforesaid application having the adjustable outlet or discharge hose 20 provided at its outer end with a valve or cutoff faucet 21. The vacuum tube or pipe 26 which is connected at its outer end with the vacuum pump 14 communicates at its other end with the receptacle 1 as explained in the aforesaid application to fill the receptacle.

The vacuum device for automatically operating the switch to open and close the motor circuit 71 comprises in its construction a bellows 70 which may be of any desired construction. The bellows 70 is mounted upon a base 73 and is provided with an intake pipe 74 which extends from the bellows to the vacuum pipe or tube 26 so that the continued operation of the vacuum pump 14, after the receptacle has been filled will exhaust the air from the bellows and close the same and move the upper board or member 75 of the bellows downwardly. This closing of the bellows by the suction of the

60

105

110

vacuum pump also moves downwardly a link 76 pivoted at its lower end at 77 to the upper board or member of the bellows and at its upper end 78 to one end of a trigger actuating lever 79. The trigger actuating lever 79 is pivoted at 80 to a depending post or support 81 provided at its upper end with a threaded shank 82 and secured by a nut in an opening in a fiber insulating head or plate 83. The fiber insulating plate 83 is supported above the base and in spaced relation with the same by corner rods 84 which may be of any desired construction and which are suitably secured at their terminals 15 to the said base 73 and to the insulating plate or head 83. The closing movement of the bellows incident to the exhausting of the air therefrom and the creating of a vacuum therein is controlled by a tension device consisting of a rod 85 pivoted at its lower end 86 to the upper board or member 75 of the bellows and extending through an opening 87 of the fiber head or plate 83 and having a coiled spring 88 disposed on its upper portion and interposed between the said fiber head or plate 83 and an adjusting nut 89. The adjusting nut 89 is mounted on a threaded portion 90 of the rod 85, a washer being preferably interposed between the nut 30 and the upper end of the coiled spring 88. By adjusting the nut 89 on the threaded portion 90 of the rod 85, the tension of the spring and the pressure resulting from the exhausting of the air from the bellows may 35 be varied and a positive action of the device insured.

The lever 79 is connected by a fiber insulating link 91 with a trigger member or lever 92 fulcrumed at one end by a pin 93 to a supporting and binding post 94 and connected by side springs 95 with a trigger member or lever 96 carrying a contact 97. The lever 79 is provided with a projecting lug 98 for engaging the trigger member 92 to limit the downward movement of the same, and the said trigger member 92 is bifurcated at its inner end as shown to straddle the binding post 94, and the adjacent end of the trigger member or lever 96. The trigger members or 45 levers 92 and 96 which are pivoted at their inner adjacent ends are provided at their outer or free ends with laterally extending arms 99 and 100 having hooked-shaped terminals for the attachment of the ends of the side springs 95. The trigger members constitute a double trigger and are adapted to swing upwardly and downwardly a sufficient distance to carry their terminals and the side springs connected therewith above and below 50 the horizontal plane of the fulcrum or pivot 93 whereby the springs operate to maintain the trigger members in either position. When the trigger members or levers are 55 swung upwardly, the contact 97 which is preferably a platinum point is carried into

and out of electrical engagement with a binding post 101 to close the circuit 71 to start the electric motor 72 and operate the vacuum pump 14, and when the trigger members or levers are swung downwardly 70 by the exhausting of air from the bellows, the contact point 97 is carried downwardly out of contact with the binding post 101 and the contact portion thereof to open the circuit 71 and stop the electric motor 72. 75 When the electric motor is in operation, the air will be exhausted from the receptacle 1 which will fill and operate vent and vacuum valves as set forth in the aforesaid application to cut off the vacuum from the receptacle and to connect the receptacle with the atmosphere so that the receptacle will empty if the valve or cut off 21 of the flexible discharge hose 20 be opened and as explained in the said application when the 80 receptacle empties the communication between the receptacle and the atmosphere is closed and the communication between the vacuum pipe or tube 26 and the receptacle is opened to reduce the vacuum within the 85 bellows by permitting the air from the receptacle to enter the bellows sufficiently to expand the same and cause the double draw trigger to close the circuit 71 and again start the motor and the vacuum pump. The 90 current for the circuit 71 may be supplied from any suitable source and the electric motor, while shown connected with the vacuum pump by sprocket gearing 102, may be connected with the said pump by any 95 other suitable gearing.

In Figures 5 to 8 inclusive, is illustrated another form of vacuum device in which a cylinder 103 and a piston are employed instead of a bellows. The cylinder 103 which 105 is preferably arranged vertically as shown is provided at its lower end with an integral head 104 and it has a removable head 105 at its other end which may be secured to the cylinder walls in any desired manner. 110 The piston comprises a vertically movable piston rod 106 extending through an opening 107 in the lower head or end of the cylinder and surrounded thereat by a suitable stuffing box 108 adapted to prevent 115 leakage of oil but any other suitable fluid may of course be employed and the said piston rod is equipped with a piston head consisting of a metallic disk or plate 110 and a clamped leather washer or member 111 which fits against the walls of the cylinder for preventing leakage of the vacuum. The cylinder is formed integral with a liquid reservoir 112 and communicates therewith by means of a passage 113 to permit 120 the oil to pass from the cylinder to the reservoir or tank 112 and vice versa as the piston moves downwardly or upwardly. The tank or reservoir is bolted or otherwise secured to a supporting ledge or flange 114 130

of a post 115 of a supporting bracket 116 provided with a base 117 at the lower end and having a supporting flange or portion 118 at its upper end to which is secured an insulating plate or head 119. The upper end or head 105 of the vacuum cylinder 103 is provided with a central opening 120 which is threaded for the reception of the lower end of an upwardly extending tube 10 or pipe 121 which is connected with and constitutes a branch of the vacuum tube or pipe 26 whereby when the vacuum tube or pipe 26 is closed to the receptacle of the gasoline filling station the vacuum pump 15 will exhaust the air in the upper portion of the cylinder and cause the piston to move upwardly in the cylinder, the pressure of the atmosphere operating on the liquid within the tank or reservoir 112 which descends 20 as the piston ascends. The liquid is adapted to prevent leakage of air into the vacuum.

The lower exterior portion of the vertically movable piston rod carries an arm 122 projecting horizontally from the piston rod 25 and connected at one end with the same by a sleeve 123 or other suitable means and having its other end 124 slotted or bifurcated to straddle a movable rod 125 slidably mounted in a vertical opening or bore 30 126 in the wall between the cylinder and the tank and extending above and below the said parts. The lower depending portion of the rod 125 is provided with upper and lower tappets 127 and 128 preferably consisting of sleeves adjustably secured to the rod 125 by set screws or other suitable fastening devices and spaced from each other above and below the horizontally projecting arm 122 of the piston rod and located 35 40 in the path of the same. The arm 122 is adapted in its upward and downward movement to engage the ends of the sleeves 127 and 128 and move the said rod 125 upwardly and downwardly a sufficient distance to effect a throw or movement of a 45 double trigger switch mechanism which is mounted upon the insulating plate or head 119. By adjusting the sleeves 127 and 128 the movement of the rod is controlled and 50 properly timed.

The piston rod is equipped with a yieldable device for controlling the pressure produced by the vacuum and for producing a positive operation of the vacuum device in 55 a downward movement of the piston for closing the electric circuit. This yieldable device comprises a plurality of weights 129 arranged upon a horizontal plate or support 130 provided with a central rod 131 extending upwardly from the plane of support and forming a hanger for the said weights. The rod is provided at its upper end with a hook 132 arranged in a slot or bifurcation 133 in the lower end of the 60 piston rod and engaging a transverse pin 65

or fastening device 134 which extends across the said slot or bifurcation. The weights are provided with radial slots 135 and one or more of the weights may be employed according to the pressure desired in the production of the vacuum. As soon as the vacuum is released the weights will operate to move the piston downwardly to the lower portion of the cylinder. The piston rod is provided adjacent to the head with a shoulder 136 constituting a stop for limiting the downward movement of the piston and preferably formed by a sleeve but any other suitable form of stop may of course be employed for this purpose. This stop prevents the piston head from descending below the upper wall of the passage 113 connecting the interior of the cylinder with the tank or reservoir.

The upper end of the vertically movable switch actuated rod or member 125 is connected by a link 137 of fiber or other insulating material with the outer end of a trigger arm or lever 138 which is pivoted at its inner end by a transverse pin or pivot 139 to a binding post 140 mounted upon the insulating head or plate 119 and also forming a support for the inner end of a trigger member or lever 141 extending from the binding post 140 in the opposite direction 95 from the trigger member or lever 138.

The trigger member or lever 140 is provided at its outer end with a contact 142 which is adapted to engage a binding post 143 for closing the motor circuit. The binding posts 140 and 143 have shanks or stems which extend through the plate or head 119 and which are threaded for the reception of clamping nuts 144 and 145 for securing the terminals of the wires of the motor circuit 100 105 110 to the said binding posts. The trigger members or levers are provided adjacent their outer ends with laterally extending arms 146 and 147 preferably provided with hook-shaped terminals similar to those of the double trigger heretofore described and adapted to engage the terminals of the side coil springs 148 located at opposite sides of 115 the trigger members or levers and adapted to be carried by the vertical movement of the rod or member 125 to points above and below the horizontal plane of the pivot 139 of the trigger members or levers whereby the springs will operate as a snap switch and will maintain the trigger members or levers 120 in either of their positions. When the rod or member 125 is moved upwardly by the formation of a vacuum within the upper portion of the cylinders 103, the trigger members or levers will be swung upwardly at the 125 upper limit of the movement of the piston and will open the motor circuit and stop the motor and the vacuum pump and when the vacuum is released and air permitted to enter the upper end of the cylinder the piston 130

will descend under the influence of the weights 129 and the rod will be moved downwardly as the piston reaches the lower limit of its movement and the switch will be moved to its closed position and the motor circuit closed for starting the motor and the vacuum pump. The contact carrying trigger arm or lever 141 is limited in its upward movement by a stop arm 149 secured to the upper portion 10 of the binding post 140 and located above and in the path of the trigger arm or lever 141. The stop arm is secured at one end to the said binding post 140 and it extends downwardly and upwardly from the same being arranged at an inclination as shown, but any other suitable means may of course be employed for limiting the upward movement of the contact carrying trigger member or lever 141. The mechanism is entirely 20 automatic in its operation, similar to that heretofore described and the vacuum will be produced in the upper portion of the cylinder when the receptacle is filled and will be released when the receptacle empties. The cylinder form of the vacuum device is simple, 25 strong and practical and is adapted to retain the vacuum condition and effectually prevent air leaking into the cylinder through the aperture through which the piston rod reciprocates.

What is claimed is:

1. A vacuum controlled electric switch for a gasoline filling station including a vacuum pump having a vacuum pipe connected with the filling station, a motor, a vacuum device communicating with the vacuum pipe and actuated by varying pressures within the same, a switch having levers or members pivotally connected at their adjacent ends and yieldable means connecting their outer portions, a contact carried directly by one of the levers or members of the switch, means for connecting the switch with the vacuum device, an electrical connection between the switch and the motor having a contact arranged to be engaged by the said contact whereby the motor is started and stopped.

2. A vacuum controlled electric switch for a gasoline filling station including a vacuum pump having a vacuum pipe connected with the filling station, a motor for actuating the pump, a vacuum device communicating with the vacuum pipe and actuated by varying pressures within the same, a switch having levers or members pivotally connected at their adjacent ends and provided at their outer portions with laterally extending arms, springs connecting the arms of the trigger members or levers, a contact carried by one of the pivoted levers or members of the switch and electrical connections between the motor and the switch having a contact arranged to be engaged by the said contact.

3. A vacuum controlled electric switch for a gasoline filling station including a vacuum

pump having a vacuum pipe connected with the filling station, a motor for actuating the pump, a vacuum device communicating with the vacuum pipe and actuated by varying pressures within the same and a switch connected with the vacuum device and controlling the motor and comprising a post or support, trigger members or levers pivoted to the support and extending in opposite directions therefrom, a spring connecting the outer portions of the trigger members or levers and arranged to swing to opposite sides of the pivot thereof and means for limiting the swing of the trigger levers or members.

4. An apparatus of the class described including a vacuum pump having a vacuum pipe, a motor for actuating the pump, a vacuum device including a cylinder communicating with the vacuum pipe, a piston operating within the cylinder and actuated in one direction when a vacuum is produced in one end of the cylinder, means for yieldably urging the piston in the opposite direction and a tank or reservoir communicating with the cylinder at the opposite end from that in which the vacuum is produced and adapted to contain a liquid to form a seal for the piston, and a circuit closer actuated by the piston for controlling the motor.

5. A vacuum controlled electric switch for a gasoline filling station including a vacuum pump having a vacuum pipe connected with the filling station, a motor for actuating the pump, a vacuum device including a cylinder communicating with the vacuum pipe, a piston operating within the cylinder and having a piston rod extending through one end of the cylinder, an arm extending from the piston rod, a movable rod or member having spaced means arranged in the path of the arm and a switch actuated by the rod or member for controlling the motor.

6. An apparatus of the class described including a vacuum pump having a vacuum pipe, a motor for actuating the pump, a vertical cylinder provided with a tank and having a passage connecting the lower portions of the cylinder and the tank, said tank being adapted to contain a liquid for forming a seal, a piston operating in the cylinder, a vertically movable rod extending through the wall of the cylinder and the tank and projecting above and below the same, means carried by the piston rod for actuating the vertically movable rod and a circuit closer connected with the upper end of the rod for controlling the motor.

7. An apparatus of the class described including a vacuum pump having a vacuum pipe, a motor for actuating the pump, a vertical cylinder connected at its upper end with the vacuum pipe and provided with a tank or reservoir communicating with the lower end of the cylinder, a piston operating within the cylinder and having a rod extending

through the lower end of the same, a vertically movable rod or member having spaced shoulders or tappets, means carried by the piston rod and operating between the shoulders of the tappets for actuating the vertically movable rod or member, a switch located above the cylinder and controlling the

motor and means for connecting the upper end of the rod with the switch.

In testimony whereof we hereunto affix 10 our hands.

CARL O. McGRAW.
JAMES L. MARTIN.
